UNITED STATES PATENT OFFICE.

JAMES A. McINTOSH, OF LA FAYETTE, INDIANA, ASSIGNOR TO THE OHIO BRASS COMPANY, OF MANSFIELD, OHIO, A CORPORATION OF NEW JERSEY.

TROLLEY-WIRE HANGER.

1,296,829.

Specification of Letters Patent. Patented Mar. 11, 1919.

Application filed February 2, 1918. Serial No. 215,014.

To all whom it may concern:

Be it known that I, JAMES A. McINTOSH, a citizen of the United States, residing at 527 S. 5th st., La Fayette, in the county of 5 Tippecanoe and State of Indiana, have invented certain new and useful Improvements in Trolley-Wire Hangers, of which the following is a specification.

My invention relates to that class of devices 10 which are known as trolley wire hangers and are intended for suspending trolley wires and more particularly with reference to catenary construction where the trolley wire is suspended below a cable.

15 My invention is one which is simple to manufacture and easy of installation and which is self-contained; that is, all parts are at all times in an assembled condition and there are no loose parts to be lost.

20 It has been found of advantage to provide a hanger which can be clenched onto the trolley wire in place of being gripped or clamped to the wire by means of bolts, screws, etc., and one of the objects of my 25 invention is to produce a hanger of this character.

To attain these ends, and the accomplishment of other new and useful objects as later set forth, my invention consists in the novel 30 features of construction, combination and arrangement of the several parts hereinafter more fully described and claimed and shown in the accompanying drawings, in which:

Figure 1 is a side elevation of my invention showing its relation to the overhead catenary or messenger cable and to the supported trolley wire.

Fig. 2 is an end elevation of Fig. 1.

Fig. 3 shows a side elevation of the hanger 40 as it is furnished the customer in which one leg of the suspending loop is secured to the ear proper and better shown by the sectional view Fig. 4 taken on the line 4—4. Fig. 3 also shows how one leg of the loop is bent 45 out to disengage the ear so that the loop can be passed over the catenary cable to install the same, and a section of this portion of my hanger is shown in Fig. 5 which is taken on the line 5—5.

50 In these figures I have shown a form of construction which embodies my invention and is my preferred form, but various modifications of my preferred form can be made without departing from the invention dis- 55 closed herein.

My invention comprises two parts—an ear part indicated by 1 and the hanger loop indicated by 2. The ear member is provided with two grooves—one to receive the trolley wire and the other to receive the bent or upset ends of the suspension member. The ear member can be made in various well known ways, such as by casting, rolling, drawing or extruding. The suspension member comprises a rod, wire, or the like. Both 60 the ear member and suspension member can be made of any material suitable but as a rule the ear member is found to work better if made of brass, bronze or copper, and the suspension member if made of iron or steel. 70

The usual method of furnishing the device to the trade is to have one leg of the suspension member indicated by 3 permanently secured to the ear member 1 and the other leg of the suspension member indicated by 4 left free of attachment to the ear member 1 as a means of convenience in installing as shown by Fig. 3.

In my preferred form the leg 3 is bent or upset at right angles and the lips 5 of the 80 ear member are bent over so as to encircle and engage that portion of leg 3 indicated by 6. This leaves the opposite end of the ear member 1 with the lips unbent.

To install my invention it is only necessary to spring the arm 4 of the suspension member outwardly and to the side so as to be free from the groove in which it rests loosely, and to then pass the suspension member loop over the messenger cable 8 and 90 then allow the leg 4 to spring back into place in the groove of the ear member.

Having done so, the operator then bends the lips 7 down over the bent or upset member 9 of the leg 4 and the hanger is then 95 installed upon the messenger or supporting cable. The trolley wire is then inserted into the groove 10 and the lips 11 are forced down into engagement with the trolley wire, securely fixing the same in place. This completes the installation of my invention.

It will be observed that not only the construction but the installation of my invention is very simple and which are results I have endeavored to attain.

While I have illustrated my invention as applied to one type of ears it will be understood that it is not limited thereto but is equally adaptable to be applied to various other well known types of ears.

It will be quite evident to those versed in the art and use of these devices that many variations from the above disclosure can be made and therefore I do not wish to be limited to the specific construction shown in the drawing and described, but to be limited by my claims only, which are as follows:—

Claims:

1. A trolley wire hanger comprising a one-piece holding member, a plurality of grooves in the holding member and a supporting member; one end of the supporting member to engage an overhead support, the other end positioned in one of the grooves and secured therein and another groove to receive and securely hold a trolley wire.
2. A trolley hanger comprising a holding member provided with a plurality of grooves positioned one above the other and parallel to each other, a suspension member to engage an overhead support and positioned in the upper groove of the holding member and secured therein, the lower groove to receive a trolley wire and the wall thereof to clench upon the trolley wire.
3. A trolley hanger comprising in combination a holding member, a plurality of grooves formed therein, one groove placed above the other and parallel to each other, the lips forming the groove to be bent or

clenched upon objects located in the grooves, a suspension member adapted at one end to engage an overhead support and provided at the other with means to engage one of the grooves in the holding member, the other groove to engage and hold a trolley wire.

4. A trolley wire hanger comprising a holding member provided with flexible lips forming a plurality of parallel grooves, a suspension member, two upset ends on the suspension member, the upset ends independent of each other for convenience in installing and positioned in one of the grooves, a portion of the lips of one groove bent or clenched over one upset end of the suspension member and a portion of the lips of the same groove adapted to be bent or clenched over the other upset end, another groove adapted to receive and hold a trolley wire.

5. A trolley wire hanger comprising a holding member provided with bendable lips forming a plurality of parallel grooves and a suspension member; the suspension member to attach to an overhead support and positioned in one of the grooves and secured by the bendable lips, another of the grooves to receive and hold a trolley wire.

In testimony whereof I affix my signature.

JAMES A. MCINTOSH.
